CLAIM

The ornamental design for a dispensing system, as shown and described.

DESCRIPTION

FIG. 1 is an isometric front, top and left side perspective view of the dispensing system showing our new design; FIG. 2 is a front elevational view thereof; FIG. 3 is a rear elevational view thereof; FIG. 4 is a left side elevational view thereof the right side elevational view being a mirror image of the left side shown; FIG. 5 is a top plan view thereof; and, FIG. 6 is a bottom plan view thereof.

It is understood that the bounds of the claimed design between the solid line profiles at the upper and lower regions are represented by the vertical extent of the contour shading lines. The broken lines are included for the purpose of illustrating portions of the dispensing system that form no part of the claim.
